LOOM

Application filed October 3, 1928. Serial No. 310,043.

This invention relates to narrow fabric looms of the type commonly used for weaving ribbons, tapes, elastic fabrics, and the like, and is concerned more particularly with the provision of driving mechanism for the multiplicity of shuttles with which such looms are provided.

In narrow fabric looms as heretofore constructed, the shuttles are mounted in guideways arranged in two rows on the batten, and each guideway has a pinion near each end which may engage rack teeth formed on the back face of each shuttle. Also mounted on the batten and extending lengthwise of a row of shuttles in the guideways is a rack bar meshing with all of the pinions. During the operation of the loom, the rack bars for the two rows of shuttles are reciprocated back and forth, and their movement causes the pinions to oscillate, resulting in the shuttles moving forward and back through their associated sheds.

One commonly used mechanism for driving the rack bars includes a pair of cranks for each rack bar connected thereto at different points by leather straps. These cranks are rocked by mechanism including elliptic and eccentric gearing and in the movement they pull the rack bar alternately in opposite directions.

This driving mechanism is open to many serious objections. The leather straps are affected by changes in the moisture content of the air and lengthen and shorten so that at one time they are too loose and at another too tight. The teeth of the rack bar and on the shuttle are of wood and they become worn and fit loosely, so that breakage occurs, and this necessitates the stoppage of the loom for repairs which are difficult and costly to make, since the ends may be damaged and loss of production occurs in any event. A further objection is that this driving mechanism does not keep the shuttles under accurate control and when the end of the throw is reached, they are likely to rebound and cause damage to the ends. The mechanism also is complicated and expensive and occupies much floor space, and the looms run with much noise and vibration.

To overcome these difficulties, I have devised a novel driving mechanism for such narrow fabric looms in which the use of complicated gearing and driving straps is avoided. This mechanism occupies little space, is simple and inexpensive to construct, has few parts, and all wearing parts are readily accessible so that adjustment or repairs are easily made. In addition, the new driving mechanism operates the shuttles with little vibration and noise, and it may be used with simple adjustments for driving shuttles in looms making many different widths of ribbon. This novel driving mechanism may be used on looms in which the shuttles are driven by the rack and pinion means referred to but for best results I prefer to employ the shuttle drive mechanism described and claimed in my co-pending application, Serial No. 208,918, filed July 28, 1927. For purposes of illustration, I have shown the new drive mechanism of this invention applied to a loom in which the shuttles are driven by the means disclosed in said application, but it is to be understood that the present invention is not limited to that particular use.

The novel drive mechanism includes a slide which is reciprocated in guideways during the operation of the loom. This slide is connected by a crank and appropriate gearing to a rock shaft fast on which is a crank arm with an adjustably mounted projecting pin. As the slide reciprocates, the rock shaft is oscillated and the crank arm and pin are caused to swing through an arc of approximately 180°. Mounted on the batten and connected to the rack bar, if the rack and pinion driving means for the shuttles are used, is a fitting having a slot into which the pin on the crank arm projects, so that as the arm is oscillated, it reciprocates the fitting and rack lengthwise of the batten.

The shuttles of a loom while reciprocated back and forth through their sheds throughout the operation of the loom are not in continuous movement but must have periods of rest at each end of their throw. During these periods of rest, the harness operates to form a new shed, after which the shuttle passes through the shed and again comes to rest.

These periods while the shuttle is at rest must be of definite duration to give the harness time to perform its function completely, and at the end of each rest period, the shuttle should start through the shed slowly, increasing its speed rapidly to a maximum and then slow down as it approaches the end of its travel so that strain on the mechanism by sudden stopping is avoided.

10 In the present mechanism, the period of rest in the shuttle movement is provided for by causing the pin on the crank arm to move through an arc of about 180° in a vertical plane, the ends of its travel lying approximately in a horizontal plane. At the beginning of its oscillation, the pin moves downwardly substantially at right angles to the direction of shuttle movement, and for a substantial part of its arc, the pin imparts 15 practically no movement to the shuttles. During such movement of the pin, the shed is forming and the parts are so co-ordinated that when the shed is completed, the pin enters a part of its arc which causes movement 20 of the shuttle through the shed. As the pin reaches the mid-point of its arc, the shuttle velocity is a maximum, and it then decreases as the pin begins to rise, until near the end 25 of its travel, substantial angular movement of the pin causes little or no movement of the shuttle.

With this arrangement, the pin has a continuous reciprocation throughout the operation of the loom, and the shuttles have a continuous simple harmonic motion. While the shuttles are in motion at all times except the instants when they change direction, they move so slowly near the ends of their throw that they may be considered at rest. This 35 result is obtained without the use of specially designed cams and the throw of the shuttles is readily variable by varying the position of the pin with relation to its center of oscillation.

40 45 For a better understanding of the invention, reference may be made to the accompanying drawings, in which

Fig. 1 is a view in front elevation of a batten with the new drive mechanism;

50 Fig. 2 is an end elevation, partly in section;

Figs. 3 and 4 are sectional views on the lines 3—3 and 4—4 of Fig. 2;

Fig. 5 is a view similar to Fig. 2 showing 55 a modified construction, and

Fig. 6 is a sectional view on the line 6—6 of Fig. 5.

60 Referring now to the drawings, the drive mechanism is illustrated as mounted on an end frame 10 of a ribbon loom provided with a batten 11 of ordinary construction. This batten includes an upper rail 12 and a beam 13 between which are mounted straps 14 to which are secured guide blocks 15 defining 65 guideways for the shuttles 16. There is a

guideway between each adjacent pair of spaces 17, where the reeds are mounted and in the loom illustrated the shuttles are mounted in upper and lower rows and the shuttles of both rows are reciprocated in unison past their associated reeds, passing through the sheds in their movement.

70 While the driving mechanism of this invention may be used with any of the standard means for moving the shuttles, I prefer to employ the construction set forth and described in my co-pending application Ser. No. 208,918, filed July 28, 1927. That mechanism includes a rod 18 extending lengthwise of the batten and lying between the shuttles of the upper and lower rows. The rod carries a plurality of plates 19 of semicircular shape which are engageable in slots 20, one near each end of each shuttle. Successive plates on the rod lie angularly spaced 180° and the rod is supported in any convenient manner on the batten but at one end it is mounted in an arm 21 extending upwardly from a slide 22 mounted in a suitable guideway in the batten. The rod is held in place in the end of the arm by collars or other suitable means so that it is free to rotate in the arm, but is held against endwise movement relative thereto. At the other end the rod extends into a tubular cam 23 having a slot 24 into which a pin 25 on the rod projects. The arrangement is such that when the shuttles are to be moved, a plate 19 on the rod is engaged in the slot in the trailing edge of each shuttle. The rod is moved endwise, advancing the leading ends of the shuttles through their sheds, and when these leading ends are disposed beyond the sheds, the rod is angularly moved through 180° , so that the plates on the rods formerly engaging the shuttles are disengaged therefrom and alternate plates are brought into engagement with the shuttles. As the plates are spaced apart a distance equal to the distance between the slots in the shuttles, it follows that after this rotational movement of the rod, each shuttle is connected thereto by a plate which enters a slot in the leading end of the shuttle. This engagement continues until the shuttles have moved to the end of their throw and on the return movement, a similar sequence of operations takes place.

105 110 115 120 In order to move the rod 18 endwise to bring about the desired shuttle movement, the slide 22 carries a plate 26, having a slotted extension 27 projecting upwardly therefrom. Into the slot projects the end of a pin 28 on a crank arm 29 fast on a rock shaft 30. The pin 28 is mounted in a slot 31 in the crank arm so that its position may be adjusted with relation to the shaft.

125 130 The shaft 30 is mounted in a journal in a bracket 32 secured to the end frame 10 and beyond the journal the shaft carries a bevel gear 33 meshing with a similar gear 34 free

to oscillate on a vertical pin 35. Secured to the hub of the gear 34 in any convenient manner is a crank arm 36. The pin 35 projects through an opening in the arm and the arm 5 is held in place by a nut 37 on the upper end of the pin. Mounted in the free end of the arm 36 by a nut 38 is a pin 39 provided at its upper end with a roller 40, which runs in a slot in a link 41 attached to the under surface 10 of a slide 42. The slide is movable in guideways 43 and on its upper surface is provided with a slotted link 44 extending parallel to the link 41. In the slot in the link 44 lies a roller 45 on a pin 46, mounted eccentrically 15 in the lower face of a gear 47 fast on a vertical stub shaft 48. The gear 47 meshes with another gear 49 on a vertical shaft 50 and gear 49 meshes with a third gear 51 on a shaft 52, this latter shaft preferably being the shaft 20 on the loom by which the jacquard mechanism, with which such looms are commonly provided, is driven. The guideways 43 for the slide 42 are mounted in a bracket 53 on the end frame member 10 and any convenient 25 mounting may be provided for the shafts 48 and 50.

With this arrangement, the rotation of the shaft 52 while the loom is in operation causes the gear 47 to rotate continuously. The pin 30 46 mounted eccentrically in the lower face of this gear and engaged in the slotted link on the slide 42 causes this slide to reciprocate in its guideways. This movement is transmitted by the link 41 to the crank arm 36 and this 35 causes the gear 34 to be rocked on its axis. The oscillation of this gear is transmitted through the gear 33 to the rock-shaft 30, causing the crank arm 29 to swing. The pin 28 on the crank arm engaging in the slotted 40 extension from the member 26 causes slide 22 to be reciprocated lengthwise of the batten and through the mechanism provided, the movement of the slide 22 causes the shuttles to be moved back and forth through their 45 sheds.

The movement of the shuttles in a loom is ordinarily not a continuous reciprocation but each shuttle comes to rest at the end of its throw in each direction, the period of rest 50 being determined by the length of time required for the new shed to form. When each shuttle starts to move in either direction, its initial movement should be slow so that the shed through which it is to pass will have an 55 opportunity to open completely and as soon as the end of the shuttle has entered the shed, the shuttle can be moved rapidly until its maximum velocity is reached substantially at the middle of its throw, after which its 60 velocity should decrease gradually so that the shuttle will come to rest at the end of its throw without jar. Another period of rest then follows until the new shed has formed whereupon the shuttle is moved back through 65 this new shed with an increasing velocity to a

maximum and a decreasing velocity so that it comes to rest gently.

In order to obtain a shuttle movement such that the shed for each shuttle will have an opportunity to form at the ends of the shuttle 70 throw, the rock-shaft lies horizontal at right angles to the plane of shuttle movement so that the crank swings in a vertical plane parallel to the direction of shuttle movement. The gearing by which this rock-shaft is 75 driven is selected so that this arm has an oscillation of substantially 180°, moving from a horizontal position in which the pin lies at one side of the rock shaft downwardly and then upwardly to a horizontal position in 80 which the pin lies at the other side of the rock-shaft.

With this arrangement, it will be seen that when the shuttles are at one end of their throw the crank arm is horizontal, but as it begins to move downwardly therefrom the pin will travel a substantial number of degrees of arc before any substantial movement is imparted to the shuttles. For example, the pin may travel from the horizontal 85 through an arc of 30°, during which time the shuttles are moved in their guideways for a short distance of the order of one quarter of an inch. After the first 30° of its arc has been traversed, further movement of the 90 crank arm begins to impart substantial movement to the shuttles and as the arm reaches the vertical position with the pin at the lowermost point of its path, the shuttle velocity is at a maximum. At this point, the 95 shuttles are in the middle of their sheds. From that point on, while the arm moves with a uniform angular movement, the motion imparted by it to the shuttles decreases 100 in velocity until at some point, for example 30°, from the end of its arcuate path, the arm begins to impart little motion to the shuttles, and this motion decreases in velocity until the arm reaches the end of its arc and begins to move downwardly again. 105

Accordingly with this driving mechanism, the crank continuously oscillates, but near each end of their throw, the shuttles are substantially at rest while the arm is moving through an upward arc and a downward arc, which may be the equivalent of these portions of its path, the shuttles are not actually stationary but the amplitude of movement is so slight that the sheds have an opportunity to form without interference and for all practical intents and purposes the shuttles may be considered at rest. 115

If desired the periods in the operation of the loom during which the shuttles are practically at rest may be increased by using 120 gearing for driving the rock shaft which causes the crank arm to have a movement through an arc of more than 180°. By such gearing the crank arm may travel, say 30° upwardly beyond the horizontal at each end 125 130

of its path of travel. If the crank arm has such a movement, it will be seen that when the arm reaches a point, for example 30° below the horizontal in its upward movement, the 5 shuttles come practically to rest. Actually they continue their movement toward the ends of their throw until the arm reaches the horizontal but this movement is so slight as to be of no importance. When the arm passes 10 the horizontal and moves upwardly beyond it, the shuttles have a slight return movement which continues until the arm reaches the end of its path of travel. Then as the arm starts downwardly, the movement of the 15 shuttles is reversed and they approach the ends of their throw again until the arm reaches the horizontal. As soon as the arm moves below the horizontal, the shuttles commence their return throw.

20 Under ordinary circumstances with the crank arm moving through 180° from horizontal to horizontal, each shuttle has a simple harmonic motion. It is not actually stationary at any time throughout the operation of 25 the loom except at the instants when it changes direction at the end of its throw but near the ends of its path of travel, the shuttle moves very slowly and may be considered to be at rest since such movement does not interfere 30 with the formation of the shed. When gearing is employed which gives the crank a greater movement than 180° , each shuttle has a simple harmonic motion with a short reciprocatory movement at each end of its 35 throw. This additional reciprocatory movement increases the period when the shuttle is practically though not actually at rest.

The throw of the shuttles required for the production of fabrics of different widths 40 may be accomplished by varying the position of the pin 28 in its slot in the arm 29, since the farther this pin is from the rock shaft 30 the greater will be the shuttle throw. In a loom for making very wide fabrics, it may 45 be necessary to employ a crank arm 29 of greater length but the choice of a crank arm and the adjustment of the pin with relation to its center of oscillation will be readily apparent. This pin is of substantial length 50 so that as the batten is oscillated toward and away from the main body of the loom in the ordinary manner, the pin will be continuously engaged in the slot in the member 26, so that the shuttles will be driven at all times 55 regardless of the batten movement.

Instead of driving the slide 42 by a revolving eccentric pin, the mechanism illustrated in Fig. 5 may be employed. In this arrangement, the gear 51 on the jacquard 60 shaft 52 drives a gear 54 on a pin 55 in bracket 56 attached to the end frame member of the loom. On the gear 54 is an eccentric pin 57 to which is connected a pitman 58 connected at its other end to a pin 59 in a slide 65 block 60 mounted in guideways 61 on a

bracket plate 62 attached to the end frame of the loom. From the under surface of the block 60 projects a pin 63 through a slot in the plate 62 and attached to the end of the pin 63 is a link 64 connected to a pin 65. 70 The upper end of this pin projects through an angularly disposed slot in 66 in the plate 62, and the lower end of the pin enters the slot in the link 44 attached to the slide 42. On the lower face of this slide is the slotted link 41 in which enters the pin 39 on the arm 36. The arm 36 drives the rock shaft 30 through suitable gearing and this rock shaft is provided with the crank arm 29 and the pin 28, as before. The various pins which enter slots may be provided with rollers and these rollers may be lubricated by oil cups 67 in the usual way.

With this arrangement the rotation of the gear 54 causes the pitman 58 to reciprocate 85 the block 60 in its guideways. This causes the pin 65 to be moved by link 64 and as this pin lies in the slot 66 disposed at an angle to the path of reciprocation of the block 60, the pin causes the link 44 and the slide 42 to be 90 reciprocated at right angles to the path of travel of the block 60. The movement of the slide is then transmitted to the crank arm 29 by mechanism previously described and the movement of this arm causes the movement of 95 the shuttles.

In certain drive mechanism for these looms which has been designed to eliminate cranks connected to shuttle driving bars, these cranks being driven by complicated elliptic 100 and eccentric gearing, cams have been employed to impart the desired movement to members connected to the driving bars. Mechanism of this type utilizing cams is generally superior to the elliptic and eccentric 105 driving means heretofore used but such cams are difficult and expensive to construct, must be formed with the greatest accuracy and in the course of time they wear so that the mechanism becomes noisy and operates with excessive vibration. In the present mechanism it will be observed that no such cams are employed but the shuttles are given a simple harmonic motion by an oscillating member which is driven by simple means, although in some instances in order to increase the period during 110 which the shuttles are substantially at rest, a movement may be imparted to them somewhat different from a simple harmonic motion as above explained.

The new mechanism is of simple construction, has few moving parts and all of these parts are readily accessible for lubrication, repair and adjustment. The mechanism is therefore inexpensive to construct, may be installed on a loom without difficulty and within a short period of time, and it occupies little space. All of the mechanism is mounted on the end frame of the loom above the floor so that it actually occupies no floor space, and 130

the floor may thus be kept clean around the end of the loom.

The drive mechanism in the form illustrated is suitable for use in looms weaving ribbon of medium and narrow widths. For the production of wide ribbons, the shuttles must be given a greater throw. This can be accomplished by lengthening the crank arm which carries the pin actuating the shuttle drive rod, or by using any suitable multiplying connection between the crank arm and shuttles.

What I claim:

1. In a loom, the combination of a shuttle and means for imparting movement to the shuttle including a member oscillating through an arc of 180° plus a small additional arc at each end of its path of oscillation, whereby the shuttle has a simple harmonic motion of 180° amplitude plus an additional movement of small amplitude and low velocity.

2. In a loom, the combination of a batten, a shuttle movable on the batten, and means for moving the shuttle back and forth, including a member oscillating in a vertical plane through an arc of 180° plus an additional arc at each end of said first arc whereby to give the shuttle a simple harmonic motion of 180° amplitude plus an additional movement of small amplitude and low velocity.

3. In a loom, the combination of a batten, a shuttle movable on the batten, a member mounted independently of the batten and movable about a center through an arc of substantially 180° plus a small additional arc at each end of the first arc, means for driving said member, and a connection between the member and the shuttle, the movement of said member imparting to said shuttle a simple harmonic motion of 180° amplitude plus an additional motion of small amplitude and low velocity.

4. In a loom, the combination of a batten, a shuttle movable on the batten, a rock-shaft extending at right angles to the direction of shuttle movement, an arm driven thereby, means for driving the shaft to impart angular movement of substantially 180° to said arm through an arc of 180° plus a small additional arc at each end of the main arc, and a connection between the arm and the shuttle, said arm imparting to the shuttle simple harmonic motion of 180° amplitude plus an additional motion of small amplitude and low velocity.

5. In a loom, the combination of a shuttle, a slide, means for reciprocating the slide, a rock-shaft oscillated by the slide, a member receiving angular movement of slightly more than 180° about a center from the rock-shaft, and a connection between the member and the shuttle, whereby the shuttle is given a simple harmonic motion of 180° ampli-

tude plus additional movements of small amplitude and low velocity occurring at each end of said motion.

6. In a loom, the combination of a shuttle, a pair of slides, means for reciprocating one of the slides, means connecting said slide to the other slide and imparting reciprocating motion thereto at an angle to the path of travel of the first slide, and means connecting said second slide and the shuttle to impart simple harmonic motion of at least 180° amplitude to the latter.

In testimony whereof I affix my signature.
HERMAN BAADER.
